PREVENTING OVERDRYING OF TERMINAL PORTIONS IN CONTINUOUS DRYING SYSTEMS

Robert M. Schaffner, Chicago, Ill., assignor to
The Guardite Corporation

Application November 22, 1943, Serial No. 511,346

4 Claims. (Cl. 34—15)

1

This invention relates to a method of avoiding overdrying or scorching of heat susceptible products in a continuous drying system.

When heat susceptible materials, such as foods, are dried in modern vacuum equipment, it is customary to use a continuous system in which progressive increments of material to be dried are introduced at one end of a long chamber and removed at the other end. Within the chamber drying is preferably accomplished under low absolute pressure in an atmosphere of steam and with radiant heat as a major source of drying energy.

While a system of this type is designated as continuous, it is in reality semi-continuous in that the amounts of any given product treated are limited and the device may not be operated beyond an eight-hour day or it may be shut down at intervals of days. In any case it has been found that the terminal portions of the train of product are customarily overdried and usually scorched because of the fact that the heat available is more than sufficient at the terminal periods and no ready method of adjusting radiant heat and steam input has been found which will take care of this factor.

In accordance with the present invention the difficulty is overcome in a very simple and effective manner by introducing into the drying progression, at each end of the progression, a substantial amount of a moistened material which is either not heat sensitive or is of such little value that overdrying or overheating of the material does not matter.

The invention is illustrated diagrammatically in the drawing in which is shown an elongated chamber 10 having an inlet door 11, an outlet door 12 and a series of tray levels 13. Trays 14 are advanced seriatim along these levels. The first trays in each lever are provided with moistened waste material 15 and the succeeding with moist heat susceptible material 16 to be dried. The chamber may be evacuated through line 17 while superheated steam is introduced at 18 and 19. Heating coils, not shown, are disposed under and over each tray level. A lock 20 is provided at each end of the chamber.

For example, in a system in which the product is introduced in thin layers in a series of trays, as described in Heineeman application 501,399, filed September 3, 1943, it has been found preferable to place in one or more of the trays in each row a paper material such as $\frac{1}{8}$ inch beaver board and saturate this material with water.

Therefore, in the operation of the system, when

the drying chamber is to be put into operation, the heating coils and vacuum and superheated steam conditions are established as closely as possible to those desired, and then the trays are introduced, but the first tray or series of trays in each tier, if there is more than one tier, is provided with the moistened paper material as described. This is immediately followed by trays filled with product to be dried and the progression is maintained in the usual fashion until for one reason or another it is to be terminated. The progression is then closed with one or more trays in each layer similarly provided with moistened waste material.

Sometimes it is desirable to provide more than one tray full of wet material. However, with trays approximately 5 to 6 feet in width, and 1 to $1\frac{1}{2}$ feet across, and employing a chamber holding 6 vertical rows of trays, and 50 to 60 feet in length, 8 trays full of moistened waste material in each tier have been found sufficient.

The effect of the moistened waste material at the opening of the progression is relatively easy to understand. Apparently the non-heating parts of the apparatus, such as the tray supports and the conveyors, become undesirably warm in the absence of wet material. The moistened waste material preceding the food products to be dried, cools such parts sufficiently to produce normal operating conditions or at least conditions sufficiently approaching normal that the deviation is not critical. In any system the amount, area, and degree of wetting of such material are correlated to bring the system into equilibrium.

At the end of the progression the effect is more indirect. There, the non-heating parts tend to become hotter after the food product being dried has passed beyond them, and the extra moist waste material serves to prevent this from happening. The overheating of these portions of the apparatus after the food has passed through them has no direct effect but indirectly serves to bring the superheated steam atmosphere to a higher temperature than is desirable.

The moistened waste material actually produces better results than if food material were passed through the drier and permitted to scorch. This is apparently because the amount of moisture available is actually made greater than would be available in a similar space of food material, and, therefore, is able to bring the heat balance into equilibrium, whereas the food material has no such surplus.

The foregoing detailed description has been

given for clearness of understanding only, and no unnecessary limitations should be understood therefrom.

What I claim as new and desire to secure by Letters Patent is:

1. The method of drying a moist organic food product in which the product to be dried is introduced to and removed from an elongated drying chamber in progressive increments at least as great in aggregate as the capacity of the chamber; characterized by introducing into the drying chamber at a terminus of the progression of increments, a substantial quantity of moistened material different from the organic food product and passing such material through the chamber as a terminus of the progression of increments, and drying it together with the organic food product to be dried therein, whereby overdrying of said terminal food product is avoided. 10

2. The method of drying a moist organic food product in which the organic food product to be 20

dried is introduced to and removed from an elongated drying chamber in progressive increments as great in aggregate as the capacity of the chamber and is dried therein under vacuum; characterized by introducing into the drying chamber at a terminus of the progression of increments, a substantial quantity of moistened material different from the organic food product and passing such material through the chamber as a terminus of the progression of increments, and drying it together with the organic food product to be dried therein, whereby overdrying of said terminal food product is avoided.

3. The method as set forth in claim 2, in which said moistened material is supplied both at the beginning and at the end of the progression of increments.

4. The method as set forth in claim 2, in which said moistened material is wet paper.

ROBERT M. SCHAFFNER.
